UNITED STATES PATENT OFFICE.

WILLIAM J. NEWTON, OF NEW YORK, N. Y.

DESIGN FOR A FUSE-CARRIER.

SPECIFICATION forming part of Design No. 28,471, dated April 12, 1898.

Application filed April 29, 1897. Serial No. 634,471. Term of patent 3½ years.

To all whom it may concern:

Be it known that I, WILLIAM J. NEWTON, a citizen of the United States, residing at New York, county of New York, State of New York, have invented a certain new and useful Design for a Fuse-Carrier, fully described and represented in the following specification and the accompanying drawings, forming a part of the same.

- In the drawings, Figure 1 is a side elevation, and Fig. 2 is a plan, of a fuse-carrier embodying my design.

The fuse-carrier has a body A of oblong shape, flat upon the top and rounded upon the edges and bottom toward the ends, and has two round screw-threaded projections B at right angles with the flat side near its ends.

The whole body is of general semi-elliptical form with the round projections upon its flat side.

The essential feature of the design is the semi-elliptical form of the body, including the round screw-threaded projections upon its flat side, substantially as shown and described.

What I claim is—

The design for a fuse-carrier, as herein described and shown.

In testimony whereof I have hereunto set my hand in the presence of two subscribing witnesses.

WILLIAM J. NEWTON.

Witnesses:

THOMAS S. CRANE,
EDWARD F. KINSEY.
